United States Patent Office

Des. 186,097

Patented Sept. 8, 1959

186,097

BAND RE-SAW

Sterling S. Smith, Seattle, Wash., assignor to Smithway
Machine Company, Inc., Seattle, Wash., a corporation
of Washington

Application March 18, 1957, Serial No. 45,312

Term of patent 14 years

(Cl. D93—3)

Fig. 1

Fig. 5

Fig. 2

Fig. 4

Fig. 5

Fig. 1 is the right hand side elevation of a band re-saw embodying my new design.

Fig. 2 is the left hand side elevation of the same.

Fig. 3 is top plan view of the machine.

Fig. 4 is a front elevation view of the machine; and,
Fig. 5 is a rear elevation view of the machine.

I claim:

The ornamental design for a band re-saw, as shown.
